QUARTZ CRYSTAL HOLDER

Joseph E. Fox, Neil A. Nelson, and William S.
Quincy, Jr., Dayton, Ohio

Application June 5, 1944, Serial No. 538,793

4 Claims. (Cl. 171—327)

(Granted under the act of March 3, 1883, as
amended April 30, 1928; 370 O. G. 757)

1

The invention described herein may be manufactured and used by or for the Government for governmental purposes, without the payment to us of any royalty thereon.

The invention to be hereinafter described relates to crystal holders of the plug-in type for radio operation.

In use in radio operation frequent changes of crystals are essential, as when the frequency of a transmitter is shifted for instance. Repair, renewal and many other causes make ready change an important consideration. To meet such requirements, crystal holders in plug-in form have been developed, facilitating such rapid substitution.

The rapidly spreading use of radio equipment to many fields includes practically all forms of transportation many of which involve high and frequent vibration and frequent or even constant exposure to dirt, dust, moisture and other damaging elements or conditions seriously affecting the operation. Penetration of moisture, for instance, may readily become fatal to the operation. Due to the wide-spread use of such holders it is important to have them of standardized, economical construction capable of low-cost mass production.

The present invention has been developed to meet the above and other requirements while at the same time eliminating the objections mentioned and producing a simple, practicable, durable and low-cost holder of the type stated.

In order to more clearly disclose the construction, operation and use of the invention reference should be had to the accompanying drawings forming part of the present application.

Throughout the several figures of the drawings, like reference characters designate the same parts in the different views.

In the drawings:

Fig. 1 is a front elevation of the invention;

Fig. 2 is a cross section on line 2—2 of Fig. 1, showing the spring in elevation;

Fig. 3 is a cross section on line 3—3 of Fig. 2;

Fig. 4 is a side elevation of the spring contacts and their mounting;

Fig. 5 is a top plan view of Fig. 4; and

Fig. 6 is an edge view of an electrode plate, the height of the raised portions being greatly exaggerated for clearness.

Referring to the drawings in detail, 1 indicates a base of any suitable material such as plastic, in which are mounted in well known manner, the usual plug-in terminals. This base may be secured to a box-like housing 2 of sim-

ilar material by any suitable attaching means such as screws 3. Preferably, internally threaded sleeves 4 embedded in 2, receive screws 3 to provide a more positive and secure connection.

Base 1 carries spaced substantially parallel, upwardly extending spring-plate or spring-leaf contact 5, each having an upper inwardly inclined or directed flange 6 and a lower inwardly directed approximately perpendicular flange 7. Between these contacts 5, as will be well understood, is disposed the quartz crystal assembly comprising the thin plate 8 of quartz crystal mounted between steel plate electrodes 9. As will be noted on careful examination of Figs. 2, 3 and 6, the crystal is spaced from the electrodes 9 throughout most of its surface. The electrodes and crystals are of approximately the same area and the same dimensions except as to thickness. The corners 10 of the electrodes 9 are slightly above the general surface. This raised portion is shown greatly magnified or exaggerated, in edge view, in Fig. 6. In assembling, the two electrode plates are disposed with their raised corners 10 facing each other and the quartz crystal between them, resting on raised portions 10 and spaced from electrodes 9 providing the necessary freedom for vibration. This sandwich assembly is placed in a plastic frame or chase 11 in the form of a hollow square or rectangle and that, in turn is placed between the contact plates 5 and between the flanges 6 and 7 thereof. In order to definitely maintain close operative assembled relations of the electrodes and crystal and definite continuous electrical contact and, at the same time, maintain the desired pressure on the quartz crystal, a coil spring 12 is interposed between one electrode 9 and the adjacent spring plate contact 5.

On reference to Fig. 3 it will be noted that 40 the chase interior dimensions are slightly greater than the corresponding dimensions of the electrodes 9 received therein. In the four corners of the frame are formed shoulders 11' which seat the corresponding electrode plate corners. This 45 mounting gives adequate spacing between the edges of the assembled electrodes and quartz crystal and adjacent sides of frame or chase 11, thereby providing greater freedom of vibration and correspondingly increased efficiency. With 50 such an arrangement, the crystal is suspended between the two electrodes by its four corners only and the entire assembled sandwich is free from contact with the enclosing chase or frame 11 except at the spacing shoulders 11' at the 55 frame corners.

Assume that the crystal and electrodes have been assembled in chase 11, chase 11 placed between spring contacts 5 and between flanges 6 and 7 thereof, and that coil spring 12 has been seated in place between 5 and 9. Next, housing 2 will be slipped down over that assembly, as an envelope. The inward taper of the upper flanges 6 assists in guiding the housing 2 to final position, coil spring 12, being appreciably compressed as the housing is forced home. Immediately prior to putting housing 2 in place, a suitable gasket 13 is slipped over the contact plates and onto base 1 in position to be clamped between base 1 and housing 2. Now, when the housing 2 is forced home, it clamps the gasket 13 against base 1. Then screws 3 are turned in and the parts drawn tightly together, gasket 13 making a moisturetight and dustproof seal between the parts.

A crystal holder constructed and assembled in accordance with this invention completely encloses all fragile parts in a container thoroughly sealed against moisture, dust and all other injurious media. The same construction and assembly provides a firm anti-vibration and jolt- or shockproof holder, proof against damage by continued severe vibration and shock when used on various types of military vehicles under the roughest and most destructive conditions.

It is believed that the construction, operation and use of the invention will be clear from the preceding description.

Many changes may be made in the construction, arrangement and disposition of various parts of the invention and in the materials used, within the scope of the appended claims without departing from the field of the invention and it is meant to include all such within this application, wherein only one preferred construction and arrangement has been disclosed by way of illustration and with no thought or intention of limiting the application thereby, and it is intended to include all such within this application.

Having thus described our invention, what we claim and desire to protect by Letters Patent is:

1. A crystal holder comprising a base provided with plug-in terminals, contact plates carried by said base and connected with said terminals, said plates having inwardly and upwardly inclined flanges and lower inwardly and perpendicularly directed flanges, a chase adapted to be mounted between said contact plates and between the

flanges thereof, a spring adapted to be compressed between one of said contact plates and the adjacent electrode plate, a moistureproof housing adapted to slip over and receive said contact plates and chase and to maintain compression of said spring, and means for securing said base and housing in moistureproof assembled relation.

2. A crystal holder comprising a base provided with terminal contacts, contact plates carried by said base and connected with said terminal contacts, said plates being provided with supporting flanges, a chase disposed between said contact plates and mounted on said supporting flanges, metal electrode plates and a quartz crystal therebetween mounted in said chase, a housing adapted to slip over and receive said contact plates and chase, means carried by the aforesaid contact plates engaging and guiding said housing to operative position and means for securing said base and housing in assembled relation.

3. A crystal holder comprising a base provided with terminal contacts, contact plates carried by said base and connected with said terminal contacts, said plates being provided with supporting flanges and housing guiding flanges, a chase disposed between said contact plates and between said supporting flanges and said guiding flanges thereof and mounted on said supporting flanges, metal electrode plates and a quartz crystal therebetween mounted in said chase, and a housing adapted to slip over and receive said contact plates and chase and means for securing said base and housing in assembled relation.

4. A crystal holder comprising a base provided with terminal contacts, contact plates carried by said base and connected with said terminal contacts, said plates being provided with supporting flanges and housing guiding flanges, a chase disposed between said contact plates and between said supporting flanges and said guiding flanges thereof and mounted on said supporting flanges, a quartz crystal mounted in said chase, a housing adapted to slip over and receive said contact plates and chase and means for securing said base and housing in assembled relation.
